UNITED STATES PATENT OFFICE.

IRVING LANGMUIR, OF SCHENECTADY, NEW YORK, ASSIGNOR TO GENERAL ELECTRIC COMPANY, A CORPORATION OF NEW YORK.

SOUND-LOCATING APPARATUS.

Application filed May 31, 1919. Serial No. 300,807.

My invention relates to the detection of sound and the determination of the direction of its source, and more particularly to the accurate determination of the direction of the source of faint sound transmitted through a liquid medium, such as water.

The direction of a source of sound is estimated or judged principally by the binaural effect produced when sound waves from the source affect both ears of the listener. This effect, which depends mainly on the difference in time of arrival of corresponding sound waves at the ears of the listener, is observed even when sound is brought to the ears through tubes such as the tubes of a stethoscope. Corresponding sound waves which do not reach both ears simultaneously produce the impression that the source of sound is on one side or the other, and the listener is able to make an approximate determination or estimate of its direction. Corresponding sound waves which arrive at both ears simultaneously produce a sharply defined impression or sensation that the source of sound is directly in front of the listener. Where the sound waves are brought to the ears through two separate and distinct tubes the relative time of arrival of the sound waves at the ears can be varied by adjusting the relative lengths of the two tubes. The listener, by making use of this well marked sensation or impression produced when the sound waves arrive at both ears simultaneously can determine with a high degree of accuracy when both sound waves arrive at the ears at the same instant.

One object of my invention is to provide apparatus in which sound collectors are placed at whatever points are most suitable, even at great distances from the listener and from one another if desired, and the sounds from the collectors transmitted to a simple and compact compensator at any point convenient for the listener. Another object is to provide a sound detecting apparatus having a greater range and better adapted for the detection of faint sounds than those heretofore used. A further object is to provide an improved compensator which is very compact and efficient and in which all connections are made to stationary parts. Another object is in general to provide im-

proved apparatus for determining the direction of the source of sound.

In accordance with my invention the sounds are carried to the listener by means of two telephonic sound collectors each comprising a transmitter, such as an inertia microphone or a magneto-phone, and a telephone receiver. The transmitters may be placed anywhere and at any distance from the listener or from each other. For example, the transmitters may be placed at the bottom of the sea on suitable tripods or supports; may be towed by a long tow line; may be submerged in deep quiet water by means of a submerged float; or may be mounted on the hull of the ship, either inside or outside. In addition the sounds may be magnified to any extent desired, thereby facilitating detection of faint sounds. To enable the listener to bring the sounds from the two sound collectors into phase so they will reach both ears at the same instant, I combine with the two telephonic sound collectors some means for varying at will the phase relations of the sounds transmitted by the collectors. This can be done by varying the phase relation of the telephonic currents in the two telephonic sound collectors, or by altering the time required for sound to travel from either sound collector to the ear. A convenient way to alter the time of travel of the sound is to alter the length of the path along which the sound waves travel. To do this I prefer to use an air compensator through which the sounds from the two telephone receivers travel along separate and distinct air paths, and by which the relative lengths of the two air paths are varied. The setting of the compensator necessary to bring the sounds from the collectors into phase so as to obtain the equalization of the binaural effect, indicates the angle which the sound wave makes with a line joining the collectors, and therefore the bearing or direction of the source of the sound may be read directly on a scale attached to the compensator.

The compensator is preferably made in the form of two concentrically mounted co-operating disks rotatable with relation to each other, one provided with two concentric grooves joined at their ends, and the other

with two projections which fit into the grooves and divide them into separate and distinct U-shaped paths along which the sound travels through the compensator to the ears of the listener. Rotation of one disk of the compensator on the other shortens one air path and lengthens the other.

To determine the true bearing of the source of sound I use at least three sound collectors 10 set out of alignment, and provide means for leading the sound from any two collectors to the ears of the listener. With each pair of collectors two bearings are obtainable, one true and the other false, but the true bearing 15 is the same with every pair of collectors while the false bearings are all different.

The novel features of my invention are pointed out with greater particularity in the appended claims but the invention itself will 20 best be understood by reference to the following specification and the accompanying drawings in which, merely for purposes of illustration, I have shown one of the various forms in which my invention may 25 be embodied and in which Fig. 1 is a perspective view of the exterior of the compensator box; Fig. 2 a cross section of the compensator box along the line 2—2 of Fig. 3; Fig. 3 a longitudinal section of the compensator box along the line 3—3 of Fig. 2; Fig. 4 a perspective view showing the bottom disk of the compensator with the top disk removed; Fig. 5 a perspective view of the under side of the top disk of the compensator; Fig. 6 a perspective view of the under side of the lid of the compensator box showing the two receivers; Fig. 7 a longitudinal section showing an adjustable bearing for the top disk; Fig. 8 a longitudinal 40 section of the attachment plug by which the electrical connections are made from the microphones to the compensator; Fig. 9 a plan view of the scale cover by which only the proper scale is exposed to view; Fig. 10 a plan view of the scale disk showing the three scales on it; Figs. 11, 12 and 13 are plan views of the scale cover and scale disk in three different positions; Fig. 14 is a diagrammatic view; Figs. 15 and 16 diagrams to illustrate a principle used in my 50 invention; and Figs. 17, 18 and 19 diagrams illustrating three different positions of the parts of the apparatus. Fig. 20 is a horizontal sectional view of a special form of compensator; Fig. 21 shows a purely acoustical system.

In the particular embodiment of my invention illustrated in the drawings the compensator is mounted in a compensator box 60 which also contains enough of the electrical equipment associated with the compensator to make a self contained unit which can at will be connected to or disconnected from the transmitters. The compensator box has a pivoted lid 21 with a lifting knob

22. Set into the lid is a metal cup shaped casing 23 containing the compensator and some of its associated parts and having a cover 24 with a window for exposing the compensator scale.

As best shown in Fig. 3, the compensator, which is sound insulated from the cup 23 by felt or similar sound insulation 25, comprises a horizontal bottom disk 26 with a perpendicular center post 27 and a cooperating top disk 28 rotatable on the bottom disk about the post 27 by means of a handwheel 29, which preferably has a smooth rim so that the operator will not know the position of the disk by the position of the handwheel. 70 A scale plate 30 on the top disk visible through the widow in the cover 24 shows the position of the top disk. The two disks are preferably made of bronze and their abutting faces must be fitted very accurately. I 80 prefer to grind them to each other finishing with rouge to get a very good surface, or in some cases bring them to an even bearing all over by lapping with a very soft abrasive, as any grit embedded in the face of either 90 disk will spoil the device.

To make two separate air paths which can be varied in length by relative rotation of the plates, the top disk has two concentric grooves 31 and 32 forming arcs of circles 95 and connected at their ends by cross channels 33 which make a gradual bend to avoid reflection of sound and are of the same cross section as the two grooves. As a matter of convenience in manufacture the grooves may 100 be cut as complete circles and then filled between the cross channels 33 with partitions 34 of soft metal such as Babbitt metal or Woods metal poured into place after the grooves have been cut. The bottom disk has 105 two blocks 35 and 36, preferably of soft metal, which make an air tight sliding fit in the grooves 31 and 32. Two inlet ports 37 and 38 on opposite sides of the block 35, and two outlet ports 39 and 40 on opposite 110 sides of the block 36 provide, in conjunction with the grooves and blocks, two distinct air paths through the compensator, one extending from inlet 37 to one end of the outer groove, through the cross channel and back 115 to the outlet 39, the other extending from inlet 38 to the other end of the outer groove, through the cross channel, and back along the inner groove to the outlet 40. If the top plate is rotated in a clockwise direction the first air path is shortened and the second is lengthened, so that the relative lengths of the two air paths can be varied to any extent desired by rotating the top disk back and forth. By using two concentric grooves 120 each air path is reflexed or bent back so that it is U-shaped and any movement of the disks affects the length of both legs of each air path. Where a very great range is desired I may use several pairs of grooves, the 125 130

two U-shaped air paths formed by each pair being connected to the corresponding U-shaped air paths formed by the next pair of grooves and so on, so that each air path through the compensator has several U-shaped portions instead of only one, and all of the U-shaped portions of one air path are simultaneously lengthened, while all those of the other air path are simultaneously shortened by angular movement of the disk. Such a compensator with two pairs of U-shaped grooves is illustrated in Fig. 20. In Fig. 20, 31', 32', 33', 34', 31'', 32'', 33'' and 34'' are the grooved passages through the compensator, and 37', 38', 39', 40', 37'', 38'', 39'' and 40'' are the ports therefor. A wide range of adjustment is obtained, yet the device is very compact. Another very marked advantage is that both the inlet and outlet ports are in the stationary bottom plate.

In the particular arrangement shown a casting 41 attached to the bottom plate is provided with inlet channels 42 in register with the inlet ports to admit the sound to the compensator and with outlet channels 43 in register with the outlet ports to carry away the sounds which emerge from the compensator. Each outlet channel opens into an outlet tube lined with felt to prevent reflection of sound. The felt such as is used on billiard tables is suitable. The felt lining 44 of the outlet tubes is backed by thin sheet metal to hold it in shape, and tapers to form a conical felt tube leading to stethoscope nipples 45 over which stethoscope tubes provided with ear tips are slipped to provide two air paths of exactly equal length to carry the sound from the compensator to the ears of the listener.

As the sounds to be detected may be mingled with other sounds and with noises from the listener's own ship and sometimes are so faint that any distortion or interference will render them unrecognizable, the compensator must change the lengths of the two air paths for the sounds without making any appreciable noise or distorting the sound waves, and without leakage from the sound passages, as very slight leakage between them decreases the sharpness of the effect. Very slight friction between metal to metal surfaces in the compensator will produce a loud grinding and roaring noise when the compensator is moved, and sufficient leakage to cause trouble will occur unless the passages are air tight. To keep the compensator quiet and tight I use between the disks a thin film of lubricant, such as castor oil, which prevents metal to metal contact, but permits noiseless movement of the disks and seals the grooves against leakage, and I also provide means for accurately adjusting the clearance between the plates.

The particular form of clearance adjusting device which I prefer is illustrated in the drawings, particularly in Figs. 1, 3, and 7. The upper plate is supported on an adjustable ball bearing which comprises a ball 46 resting in a slight cup or depression in the upper end of the post 27. The lower end of an adjusting plug 47 screw threaded into the handwheel 29 rests on the ball 46. By rotating the adjusting screw 47 all or part of the weight of the top disk can be carried on the ball 46, and the clearance between the top disk and the bottom disk regulated to a nicety.

As the compensator is air tight shortening one air passage and lengthening the other causes pressure variations which produce an unpleasant effect on the ear drums of the listener and also interfere with listening. To minimize these pressure changes without appreciably weakening the sound waves or altering their characteristics, I provide for each air path a tubular relief vent 48, best shown in Fig. 3, of such a bore that it relieves the pressure and of such a length that practically none of the sound waves escape through it. I have found by experiment that a vent tube about two inches long and with a bore about $\frac{1}{8}$ inch will relieve practically all of the objectionable pressure variations without modifying the sound waves. The column of air in the vent tube has so much inertia that it is but little affected by the comparatively rapid variations of pressure due to sound waves, but yields to the slow sustained pressure produced when the compensator is moved. If the vent tube is very short, or a vent hole is made in a thin walled tube, the air in the vent yields to the pressure variations of the sound waves, and sound is lost. In addition, resonance effects are produced and the quality of the sound altered.

To catch surplus oil, pads of absorbent material may be placed at the lower ends of the inlet and outlet channels. A convenient way of holding this material is in removable cups threaded into the lower ends of the channels, or in some cases the material may be packed around the vent tubes 48.

My compensator may be used where the sound is transmitted telephonically, as in the particular arrangement illustrated, or acoustically along an air path from the sound collector to the compensator by tubing, because the compensator itself introduces no disturbing noises and does not alter in any way the characteristics of the sounds passing through it.

In the embodiment illustrated the sounds are delivered to the two inlet channels 42 by two telephonic receivers 49 and 50 connected to submerged transmitters. These receivers must be connected so that their polarity will be the same, otherwise a compressional sound

wave in one air path will correspond to a rarefactive sound wave in the other path, and serious errors will be produced.

By my invention three transmitters are used and to connect at will any two of these three transmitters to the two receivers I provide means, such as a transfer switch, for controlling the electrical connections. The particular transfer switch illustrated is mounted, as shown in Fig. 3, inside the casing 23, concentric with the compensator, and comprises an upper ring, consisting of three insulated segments 51^a, 51^b, and 51^c, a middle ring 52 connected to receiver 49, and a lower ring 53 connected to the other receiver 50, these rings being mounted on but insulated from the wall of the casing. A set of brushes 54 and 55 for connecting the segments to the middle ring and another set of brushes 56 and 57 for connecting the segments to the bottom ring are mounted on brackets 58 of a brush holder ring 59 rotatably mounted on an annular boss 60 on the bottom of the casing. A handle or pointer 61 immediately beneath the handwheel of the compensator and above the cover of the casing moves a plate or scale cover 62 which, through pins 63 entering slots 64 in the brackets 58, shifts the brush holder ring 59 as the handle 61 is moved, so that the pointer or handle 61 shows the position of the transfer switch. The pins 63 and slots 64 are so related that the parts cannot be assembled in wrong relation. The scale-cover 62 moves in synchronism with the brush holder ring, and exposes the proper one of the three scales A, B and C on the scale plate 30.

The connections of the transfer switch and of the electrical devices mounted in the compensator box will best be understood from Fig. 14 which is a diagram of the electrical connections to the three microphone transmitters *a*, *b* and *c*. The transfer switch is shown in position to connect transmitters *a* and *b* to the receivers 49 and 50, while transmitter *c* is idle. The three segments 51^a, 51^b and 51^c of the transfer switch are connected through condensers 65^a, 65^b and 65^c to contact brushes 66^a, 66^b and 66^c and also through reactances 67^a, 67^b and 67^c to a common terminal of two supply batteries 68 and 69. Either one of these batteries can be used at will by operating an interchange switch 70, which is connected, through an operating switch 71 shunted by a condenser 72, to a contact brush 73. For convenience in measuring the potential of the supply battery, I provide a voltmeter *V*. To illuminate the scale I may use a scale lamp 74 lighted from a lamp battery 75 by means of a push button 76 on the lid 21 of the compensator box. All of the parts of the device above described are contained in the compensator box 20 and form a compact portable unit which may be

connected to and disconnected from the transmitters at will.

The electrical connections to the three microphone transmitters may be made in various ways, but I prefer to use an attachment plug 77 adapted to be inserted in the compensator box and to cooperate with the four contact brushes in the box. As shown in Fig. 8 and illustrated diagrammatically in Fig. 14, this plug 77 has an insulated conducting sleeve 78 and three insulated conducting rings 79^a, 79^b and 79^c. The plug is connected through a four-conductor cable 80 to the three microphone transmitters *a*, *b* and *c*, each connected at one terminal through a conductor of the cable to the conducting rings 79^a, 79^b and 79^c, respectively, and at the other terminal through a common connection 81 and the fourth conductor of the cable to the sleeve 78 of the plug. When the attachment plug is inserted in the box the conducting rings 79^a, 79^b and 79^c are connected, respectively, to the contact brushes 66^a, 66^b and 66^c, and the sleeve 78 is connected to the contact brush 73.

The three microphone transmitters or sound collectors *a*, *b* and *c* may be of any desired type which is relatively non-resonant. Rubber and similar material may be used to advantage, and I prefer to use a transmitter of the inertia type mounted on a soft rubber diaphragm which forms one wall of a closed chamber containing the microphone. A suitable type is shown in my Patent No. 1,475,190 granted Nov. 27, 1923.

The transmitters are mounted at the angles of an equilateral triangle, and may be placed at any convenient distance from each other. Good results have been obtained where they were as close as 18 inches, and as far apart as 50 feet. The further they are apart the more accurately can the direction be determined. The transmitters can be placed on a frame or tripod placed on the bottom of the sea at any desired distance from the compensator on shore; can be mounted on a frame carried by a submerged float which keeps them 50 or 60 feet below the surface where the water is comparatively quiet; may be towed from the ship, or may be mounted in water or oil tanks to collect sound vibrations transmitted from the sea water through the ship's plating to the water or oil in the tanks. As the location of the transmitters does not depend on that of the compensator, the transmitters and the compensators can be located in the best positions without reference to each other.

Direct current from the supply battery flows through all of the microphone transmitters through a circuit containing the reactances 67^a, 67^b and 67^c. When the voltage drops below the proper amount the

shifting switch 70 should be used to connect in the other supply battery. Before shifting from one supply battery to the other, or before removing the attachment plug, the operating switch 71 should always be opened, as this switch is shunted by a condenser 72 of sufficient capacity to prevent the coherer action and packing of the carbon particles which occurs and causes the microphone to lose its sensitiveness if the supply battery circuit is broken at any other point.

It is often desirable to arrange the circuits so that when any two of the microphones are connected to the receivers the third microphone is connected through a resistance, or resistance and inductance, equivalent to that of one of the receivers, so that the circuit through each microphone is maintained practically constant regardless of the position of the transfer switch. One way of doing this is to provide the brush holder ring 59 with a brush 82 connected through inductance and capacity to the terminal of the supply battery, as indicated diagrammatically in Fig. 14. In practice the connection may conveniently be made through the metal of the compensator. In this manner I avoid the change in sensitiveness which sometimes occurs when a microphone is first switched into circuit, as the sensitiveness of the microphone sometimes changes for a few minutes after it is first put in circuit until the conditions in the circuit become stable.

The mode of operation of my invention will be better understood by first considering the diagrams shown in Figures 15 and 16, which illustrate its general principle. Referring first to Fig. 15, let D and E be two transmitters submerged in the water and connected as previously described to the two receivers 49 and 50. In effect the listener at the compensator faces the point T, with his left ear hearing sound from transmitter D and his right ear hearing sound from transmitter E. Let the hearings be taken on a scale of which the zero point is on the line OT.

A sound wave in the water spreads in a circle from its source, but in practice the source is always so far away that when the sound wave arrives at the transmitters D and E the sound is in the form of a plane wave whose plane is perpendicular to the bearing or direction of its source. Suppose a sound wave originates at a source T which is some distance away. This wave, traveling from T to O with its plane perpendicular to the line OT will reach both transmitters at the same instant, producing corresponding sounds from both receivers at the same instant. If the compensator is set in its middle position, as indicated diagrammatically in Fig. 14, so that both of the air paths through it are of the same length, the sounds

emitted by the two receivers at the same instant will reach both ears of the listener at the same instant, and he will receive the impression that the source of sound is directly in front of him.

However, a precisely similar effect will be produced by a sound originating at a source S, because a sound wave from the latter source would also reach the two transmitters D and E at the same instant. Under the conditions just assumed the listener knows that the source of sound is somewhere on the line TS, and that its bearing is either zero or 180 degrees, but he does not know which bearing is the true one.

Now assume that the source is at X. Let the plane of the sound waves, which is perpendicular to the line OX, be represented at the instant the wave reaches the transmitter E by the full line Ex. The wave will reach the other transmitter D some time later, as it still has to travel the distance Dx, which depends upon the angle the line OX makes with the line DE. If this distance Dx can be measured the bearing of the source will be known. As the speed of the sound wave in the medium in which it travels is known, and the time at which the sound wave reaches transmitter E differs from that at which it reaches transmitter D by the time required for the sound to travel this distance Dx in water, a measurement of this time difference or interval will give the distance Dx, and therefore the bearing of the source of sound. When the listener hears the sound from transmitter E first, he gets the impression that the source is somewhere to the right of him. By turning the compensator to the right, that is, clockwise, it may be set to bring the sound from both transmitters to both ears at the same instant. The extent of movement of the compensator measures the time interval due to the distance Dx and therefore its setting indicates the distance Dx. The sound wave travels about 4.4 times as fast in water as it does in air. Suppose the path in air over which the sound from transmitter E reaches the listener's right ear is lengthened by an amount equal to $\frac{1}{4.4}$ of the distance Dr.

The sound will require just the same time interval to travel this extra length of path in air that it requires to travel the distance Dx in water, consequently the sound from transmitter E traveling over the lengthened air path will reach the right ear of the listener at the same instant as the sound from transmitter D reaches his left ear. The proper lengthening of the air path is brought about by moving the compensator until the listener gets the impression that the source of sound is directly in front of him. As the maximum time interval be-

tween the sound from the two transmitters occurs when the sound wave comes from a source in alignment with the transmitters, the compensator must be of such a size that the length of either air path can be varied at least $\frac{1}{4.4}$ of the distance between the two transmitters to compensate for the time required for a sound wave in water to travel from one transmitter to the other. As the extent of movement of the compensator depends upon the time interval between the sound from the two transmitters, and therefore upon the distance D_w , the setting of the compensator indicates the bearing of the source of sound. However, with this same setting of the compensator the same effect is produced on the listener if the sound wave comes from a source W , because the sound wave from this latter source would also strike transmitter E before it strikes the other transmitter D and at the instant it strikes transmitter E it must go a distance D_w before it strikes the other transmitter D . As this distance D_w is equal to the distance D_x , sound from either source X or source W produces the same effect, so when the listener gets the impression that the source of sound is directly in front of him he can not tell whether the bearing X or W is the true one.

For the same reasons sound from either source Z or source Y will give the same effect. When a sound wave from source Z strikes transmitter E , it still has to travel a distance D_z before striking the other transmitter, and when a sound wave from a source Y strikes transmitter E , it also has to travel a distance D_y before striking the other transmitter D . As these two distances D_z and D_y are equal, one setting of the compensator will give the same effect from either source.

There is no ambiguity if the source is in alignment with the transmitters D and E but the bearing of such a source cannot be read very accurately, because a very slight error in setting the compensator makes a large error in the bearing.

The bearing as read upon the scale of the compensator depends upon the angular relation of the two transmitters to the line of reference. For example, let the two transmitters be swung clockwise from the positions indicated in Fig. 15 about the point O , as a center through an arc of 120° into the position indicated in Fig. 16. Let the source of sound be T the same as is Fig. 15. Due to the different relations of the transmitters to the reference line the compensator must be set in a different position than in Fig. 15, to give the impression that the source T is directly in front of the listener, and the scale of the compensator must also be different, so as to read zero for sound from the source T . The other source S , which will

give the same effect with the compensator in this position, will have on this compensator scale a bearing of 60° degrees.

The operation of my invention will best be understood in connection with Figs. 17, 18 and 19, which show diagrammatically the electrical connections and the three different positions of the transfer switch and the compensator. In these diagrams the line of reference is assumed to be the same as in Fig. 15, perpendicular to the line joining the transmitters a and b , with zero of the azimuth circle above this line. The source of sound which is to be located is assumed to be T and the bearing of this source of sound is assumed to be 50° degrees.

For convenience the operation of locating the source of sound T will be begun with the transfer switch in the C position, in which it is shown in Figs. 1, 2, 3 and 14. In this position transmitter c is idle, and transmitters a and b are connected to receivers 49 and 50, respectively. In effect the listener is facing transmitter c . The scale cover is in the position shown in Fig. 12, exposing the "C" scale only.

The sound wave from the source T will travel in the water toward the transmitters with its crest perpendicular to the line OT . This sound wave first reaches transmitter b and sets up currents which flow, through the connections shown, to receiver 50 which thereupon emits a sound corresponding to the sound wave in the water. This sound wave in air emitted by the receiver 50 enters the compensator through the inlet channel 42 and inlet port 38, travels along the right hand air path in the compensator to the outlet port 40 and outlet channel 44, and thence to the right ear of the listener. As explained in connection with Fig. 15 the sound wave in water has not at this time reached transmitter a , but will reach it later. The listener receives the impression that the source of sound is to the right. He turns the hand wheel to the right, that is, clockwise, into the position indicated diagrammatically in Fig. 17. This movement of the compensator lengthens the right hand air path and shortens the left hand air path and the source of sound thus apparently moves toward the left until it seems to be directly in front of the listener. In this position of the compensator the sound which starts early from the receiver 50 and travels over the long right hand air path arrives at the right ear of the listener at the same instant that the sound which starts later from the receiver 49 and travels over the short left hand air path reaches the left ear of the listener.

In practice the compensator is swung back and forth in swings of decreasing amplitude until the sound seems to be centered. This binaural effect enables the listener to determine very accurately when the compensator is 120 degrees from the reference line. The transfer switch is then moved to the B position, in which it is shown in Figs. 1, 2, 3 and 14. In this position transmitter b is idle, and transmitters a and c are connected to receivers 49 and 50, respectively. In effect the listener is facing transmitter c . The scale cover is in the position shown in Fig. 12, exposing the "B" scale only.

set properly to compensate for or neutralize the difference in time at which the sound wave in the water reaches the two transmitters *b* and *a*.

5 As pointed out in connection with Fig. 15, this setting of the compensator gives the same effect for sound from a source T and from a source F. If the bearing of the source T is 50 degrees an application of the 10 principles explained in Fig. 15 will show that the bearing of the other source F, or the false bearing OF, is 130 degrees. The scale is graduated to read both 50 degrees and 130 degrees for this setting of the compensator, 15 and the listener knows that the source of the sound to which he is listening is on one of these two bearings, but he does not know which is the true bearing and which is the false bearing. He, therefore, reads the position of the compensator on the C scale as 20 either 50 degrees or 130 degrees.

The next step is to shift the transfer switch to another position, and for convenience we will assume that it is shifted to the 25 A position, thereby rendering transmitter *a* idle, putting transmitters *b* and *c* into service, and setting the scale cover in the "A" position, shown in Fig. 10, to expose the "A" scale. At the same time the electrical 30 connections are changed as indicated diagrammatically in Fig. 17, so that transmitter *b* is connected to the left ear through receiver 49, and transmitter *c* is now connected to the right ear through receiver 50. In effect the listener is now facing transmitter *a*. Under these conditions the sound wave from the source T reaches transmitter *c* only a 35 very short interval of time before it reaches transmitter *b*, and consequently a very slight movement of the compensator from its middle position will compensate for this difference in time. The setting of the compensator in this position is therefore near the middle as indicated in Fig. 18. In this position of the compensator sound from a 40 source T having a bearing of 50 degrees produces the same effect as sound from a source F having a bearing of 250 degrees, but again the listener does not know which is the true bearing and which is the false one. However, the bearing of 50 degrees of the 45 source T is the same as the bearing of T determined in the C position, while the false bearings are different. This result indicates to the listener that 50 degrees is the true bearing when he reads upon the A scale that the bearing of the source of sound is either 50 degrees or 250 degrees.

The final step is to shift the transfer switch into the B position indicated diagrammatically in Fig. 19 to render *b* transmitter idle, put into service the transmitters *c* and *a*, and expose the "B" scale, as indicated in Fig. 11. In the B position transmitter *c* is connected through receiver 49 to

the left ear of the listener, the reverse of its connection in the A position, while transmitter *a* is connected to the right ear of the listener through receiver 50, the reverse of its connection in the C position. In effect 70 the listener is now facing transmitter *b*.

The sound from the source T first reaches transmitter *c*, and as the line OT is almost parallel to the line *ac*, the time interval elapsing between the arrival of the sound 75 wave at the transmitter *c* and its arrival at the transmitter *a* is nearly a maximum. To compensate for this great difference in time the compensator must be moved to its extreme position as indicated diagrammatically in Fig. 19, so that the air path from receiver 49 to the left ear of the listener is 80 very long, while the air path from receiver 50 to the right ear of the listener is very short. 85

In this position of the compensator, the same effect is produced by sound from source T or from source F. The true bearing OT is 50 degrees, while the false bearing OF is 10 degrees, and since the source of sound 90 may be on either one of these bearings the B scale which the operator reads is graduated so that in this position of the compensator the bearing is read as either 50 degrees or 10 degrees. The bearing of the 95 source T agrees with the true bearings determined in the C position and in the A position, while the bearing of the source F of 10 degrees is a false bearing which does not agree with either of the other false bearings 100 determined in the other two positions. This result proves that the true bearing is 50 degrees.

My invention may be embodied in other than the preferred form illustrated. The 105 transmitters *a*, *b* and *c* may be replaced by underwater collectors of rubber or similar material, and the sound transmitted acoustically to the compensator; any two of the collectors being connected at will to the inlet ports of the compensator by valve mechanism, such as a rotary valve. Such a structure is shown in Fig. 21 where *a'*, *b'* and *c'* designate rubber bulbs mounted on a frame 110 81 and connected to a rotary valve 83 by 115 tubes 82^a, 82^b and 82^c. The rotary valve 83 is connected to the compensator 86 by means of the flexible tubes 84 and 85. The transfer switch may be made in various forms; and other changes in details may be made. I, 120 therefore, do not wish to be restricted to the form shown, but intend to cover all changes and modifications within the spirit of my invention and the scope of the appended claims. 125

What I claim as new and desire to secure by Letters Patent of the United States, is:

1. The combination with two sound transmission systems each composed of an elec- 130

trical transmitter connected to a receiver and of a fluid column through which the sound is transmitted, of means for varying the relative conditions of said two fluid columns at will to bring out of phase sounds in said two systems into phase and thereby produce the binaural effect.

2. The combination with two sound transmission systems each composed of an electrical transmitter connected to a receiver and of an air path for transmitting the sound emitted by the receiver, of means for varying the relative lengths of said air paths to vary the phase relation of the sounds which traverse said air paths.

3. The combination with a compensator for adjusting the relative lengths of two independent air columns, of a telephonic system for transmitting sound from one point to one of said air columns and from another point to the other air column.

4. In a device of the character described, the combination with two telephonic transmitting systems each comprising a transmitter connected to a receiver and adapted to be submerged in a fixed position, of a compensator for varying the phase relation of the sounds emitted by said receivers and thereby bringing said sounds into phase when delivered by the compensator.

5. A compensator comprising two relatively movable flat plates, one of said plates having two channels side by side and parallel to the direction of movement of the plate and joined at their ends, and the other plate having two projecting blocks fitting into said parallel channels with two ports on opposite sides of each block.

6. A compensator comprising two relatively rotatable disks one provided with an endless channel formed by two grooves forming arcs of circles concentric with the axis of rotation of one of said disks and joined at their ends by cross channels, and two blocks on the other disk fitting into said grooves to divide said grooves into two reflexed channels, the length of one of said channels being increased and that of the other being decreased by rotation of said disk.

7. A compensator comprising two flat disks mounted to rotate about a common axis, one of said disks having two pairs of ports adjacent each other and at different radial distances from the center of said disk, and two projecting blocks in radial alignment, one block between the ports of each pair, and the other disk having two grooves concentric with said axis and shaped to fit snugly over said blocks, said grooves extending part way around the disk and being joined by a cross channel at each end.

8. A compensator comprising two relatively rotatable disks provided with coop-

erating grooves and blocks to form two separate air paths inversely variable in length by relative movement of said plates, transfer means for at will delivering sound from any two of three different points to said compensator, a scale plate having three scales and movable to show the relative rotation of said disks, a scale plate cover constructed to show only one scale at a time, and means for causing said switching mechanism and said cover to move in synchronism to expose only that scale which corresponds to the position of the switching mechanism.

9. The combination with a compensator comprising two relatively rotatable disks, and a scale plate movable with one of said disks and having three concentric scales, of a switching mechanism comprising an annular rotatable brush holder mounted concentrically with said disks, three insulated collector rings mounted one above the other concentric with said brush holder, one of said rings being divided into three insulated segments, a bridging brush on said holder cooperating with said segments and one of said rings, and a second bridging brush cooperating with said segments and the other ring, a scale cover connected to said brush holder and constructed to expose only one of the scales on said scale plate at a time, and means for shifting said scale cover and thereby shifting said brush holder.

10. In a device of the character described the combination with a compensator comprising two relatively rotatable disks provided with grooves and cooperating blocks to form two air paths through the compensator variable in length by relative rotation of said disks, two telephone receivers in communication with the two air paths through the compensator, a switching mechanism comprising three segments insulated from one another and means for connecting any one of said segments to one receiver while the adjacent segment is connected to the other receiver, and three stationary contacts connected through condensers to said three segments and through resistances to a source of current.

11. The combination with a compensator having two separate sound paths relatively variable at will to alter the phase relation of the sounds in the two paths, of three sound collectors mounted out of alignment, means for transmitting sound from each of said collectors to said compensator, and means for at will connecting any two of said collectors to the two sound paths through the compensator.

12. The combination with a compensator having two separate air paths for sound through it and means for at will varying the relative lengths of said air paths, of three sound collectors mounted out of align-

- ment, means for transmitting the sound from each collector to said compensator independently of the sound from any other collector, and means for at will connecting any two of said collectors to the two air paths through the compensator whereby the compensator may be adjusted to bring the sounds from any two collectors into phase and thereby produce the binaural effect.
10. 13. The combination with two receivers, three transmitters mounted out of alignment and electrical connections between said transmitters and said receivers whereby said receivers may be connected to any two of said transmitters, of a compensator for varying the phase relation of the sounds emitted by said receivers to bring said sounds into phase when delivered by said compensator and thereby produce the binaural effect.
15. 14. The combination with two receivers, three transmitters set out of alignment, electrical connections between said transmitters and said receivers, and a switch for at will connecting said receivers to any two of said transmitters, of a compensator for varying the phase relation of the sounds emitted by said two receivers to bring said sounds into phase when delivered by the compensator.
20. 15. A compensator comprising two relatively rotatable disks having cooperating grooves and blocks which form two air paths variable in length by relative rotation of said disks and a vent for said paths having such a relation between length and bore that air pressure is relieved without escape of sound.
25. 16. The combination with a telephonic sound transmitting system comprising a microphone transmitter connected to a receiver and a battery connected in circuit with said microphone, of a switch for opening and closing said circuit through the microphone and a condenser shunting said switch and of sufficient capacity to prevent coherer action in the microphone when said circuit is opened.
30. 17. A compensator having two relatively movable members cooperating to form an air passage varied in length by movement of said members, a continuously open vent for relieving air pressure in said passage, said vent comprising a long and narrow passage which is adapted to prevent the escape of sound waves.
35. 18. A compensator having two relatively movable members cooperating to form an air passage varied in length by movement of said members, and a tubular vent for said passage of such bore and length that air under pressure escapes and sound waves are retained.
40. 19. An apparatus for the determination of the direction of travel of vibrations comprising three receivers of vibrations out of line, a compensator, means for operatively connecting one pair of the three receivers to the compensator, and thereafter operatively connecting with the compensator a different pair of the three receivers.
45. 20. The combination of a compensator having two passages for energy, relatively variable to vary the relative time of travel therethrough, three receivers of wave energy mounted out of line, means for successively connecting at will different pairs of said receivers to the two passages through the compensator.
50. 21. The combination of a compensator having two separate air passages for sound therethrough and means for varying the relative lengths of the air passages, three sound receivers mounted out of alignment, means for connecting at will one pair of said receivers to the air paths of the compensator, or a different pair of said receivers to said air paths, so as to deliver to the compensator sounds corresponding to those received by one of the other of said pairs of receivers as desired.
55. 22. Apparatus for the binaural determination of the direction of sound in water, comprising three spaced telephonic transmitters out of line, two ear pieces, two energy transmitting connections connected respectively at one end to said ear pieces, and connectable respectively at the other end first to one pair of said transmitters and then to a different pair of said transmitters, and means for varying the effective relative lengths of said energy transmitting connections.
60. 23. Apparatus for the binaural determination of the direction of travel of sound comprising two air paths for sound, means for relatively varying the lengths of said paths, two telephonic receivers, one for each air path to deliver sound thereto, three sound collectors out of alignment each comprising an electrical telephonic transmitter, and means for successively connecting at will different pairs of said transmitters to the two receivers.
65. 24. An acoustic device consisting of a relatively fixed and a relatively movable member, two paths for sound waves extending oppositely through said device, each path comprising two parallel portions and having both its inlet and outlet openings in the fixed member and at least a portion of its length in the movable member, so that relative motion of the relatively fixed and movable members causes an equal and inverse variation in the lengths of the two passages.
70. 25. An acoustic device comprising a relatively fixed member having two inlets for sound and two outlets for sound, and a relatively movable member having two oppositely extending passageways for sound, each passageway comprising two parallel portions and a connecting portion, one of the two parallel portions of each passageway

communicating respectively with one of the inlets for sound and the other parallel portion of each passageway communicating respectively with one of the outlets for sound, whereby relative motion of the relatively fixed and movable members causes an equal and inverse variation in the lengths of the two passageways.

26. An acoustic device comprising a relatively movable member having two parallel passageways connected together at their opposite ends, a relatively fixed member having two inlet openings for sound waves communicating with one of the parallel passageways and two outlet openings for sound waves communicating with the other of the parallel passageways, sound obstructing means in the passageways between the inlet openings and between the outlet openings so as to form two oppositely extending rebent passageways for sound whereby relative motion of the relatively fixed and movable members causes an equal and inverse variation in the lengths of the two sound passageways.

27. An acoustic device comprising a fixed and a movable member having mutually engaging surfaces upon which the movable member is slidable with respect to the fixed member, two paths for sound waves extending oppositely through said device, each path comprising two parallel grooves in the engaging surface of one of the members and a passage connecting said grooves, and each path having both its inlet and its outlet in the fixed member and at least a portion of its length in the movable member, so that relative motion of the two members causes an equal and inverse variation in the lengths of the two paths.

28. An acoustic device comprising a fixed and a movable member having mutually engaging surfaces upon which the movable member is slidable with respect to the fixed member; two paths for sound waves extending oppositely through said device, each path comprising two parallel grooves in the movable member and a passage connecting them; two inlet ports for sound and two outlet ports for sound all located in the fixed member; one of the two parallel grooves of each passageway communicating respectively with one of the inlet ports for sound, and the other parallel groove of each passageway connecting respectively with one of the outlet ports for sound; whereby movement of the movable member causes an equal and inverse variation in the lengths of the two passageways.

29. A compensator comprising a rotatable member and a fixed member having mutually engaging surfaces which are maintained in sliding contact as the rotatable member rotates with respect to the fixed member; two channels formed in the engaging sur-

face of one of the members which channels are parallel to the direction of motion of the movable member and are connected at their ends by cross-passages; two sound obstructing means projecting from the engaging surface of the other member and fitting respectively into the two channels so as to form two oppositely extending rebent passageways; and ports in the member from which the sound obstructing means project, said ports connecting with said channels and located one on each side of each sound obstructing means.

30. A compensator comprising a rotatable member and a fixed member having flat mutually engaging surfaces which are maintained in sliding contact as the rotatable member rotates with respect to the fixed member; two curved channels formed in the engaging surface of one of the members which channels are parallel to the direction of motion of the movable member and are connected at their ends by cross-passages; two sound obstructing means projecting from the engaging surface of the other member and fitting respectively into the two channels so as to form two oppositely extending rebent passageways; and ports in the member from which the sound obstructing means project, said ports connecting with said channels and located one on each side of each sound obstructing means.

31. Apparatus for the determination of the direction of travel of sound comprising two spaced telephonic sound collectors, each comprising an electrical transmitter, an electrical connection from each transmitter to a receiver, a fluid path from each receiver, means for relatively varying the fluid paths to vary the relative time of travel of sound therethrough.

32. The combination with a compensator for adjusting the relative lengths of two independent air columns, of an electrical telephone system for transmitting sound from one point to one of said air columns and from another point to the other of said air columns.

33. Apparatus for binaural determination of the direction of travel of vibrations comprising two separated non-resonant receivers of vibrations for respectively causing variations in two electric currents corresponding to the received vibrations, ear pieces, one for each ear of the observer, energy transmitting connections between the respective receivers and ear pieces.

34. Apparatus for binaural determination of the direction of travel of vibrations comprising two separated non-resonant receivers of vibrations for respectively causing variations in two electric currents corresponding to the received vibrations, ear pieces, one for each ear of the observer, energy transmitting connections between the respective

receivers and ear pieces, and adjustable means in one or more of such connections whereby the time of travel from one receiver to the corresponding ear piece can be varied with respect to the time of travel from the other receiver to its corresponding ear piece.

35. Apparatus for the binaural determination of the direction of sound in water comprising two spaced electrical telephone transmitters, constituting non-resonant receivers of vibrations, two ear pieces, energy

transmitting connections between the respective transmitters and ear pieces, and adjustable means in one or more of such connections whereby the time of travel from one transmitter to the corresponding ear piece can be varied with respect to the time of travel from the other transmitter to its corresponding ear piece.

In witness whereof, I have hereunto set my hand this 29th day of May 1919.

IRVING LANGMUIR.
